US0D1079165S

(12) **United States Design Patent** (10) Patent No.: **US D1,079,165 S**
(45) Date of Patent: ** Jun. 10, 2025

(54) **STORAGE BASKET FOR HOUSEHOLD PURPOSE**

(71) Applicant: **Zhejiang Zhihuijia Technology Co., Ltd.**, Taizhou (CN)

(72) Inventor: **Caifen Lu**, Zhejiang (CN)

(**) Term: **15 Years**

(21) Appl. No.: **35/521,979**

(22) Filed: **Jun. 3, 2024**

(80) **Hague Agreement Data**

Int. Filing Date: **Jun. 3, 2024**

Int. Reg. No.: **DM/238974**

Int. Reg. Date: **Jun. 3, 2024**

Int. Reg. Pub. Date: **Aug. 16, 2024**

(51) **LOC (15) Cl.** 09-04

(52) **U.S. Cl.**

USPC **D32/37; D3/307**
